CLAIM

USPC **D6/716.4**

We claim the ornamental design for the chair frame, as shown and described.

(58) **Field of Classification Search**

DESCRIPTION

USPC D6/334-336, 364, 365, 366, 367, 374,
D6/376, 379, 380, 716, 716.1, 716.2,
D6/716.3, 716.4; 297/284.4, 298, 411.27,
297/452.21, 452.29, 452.3, 452.32, 452.34,
297/452.48

FIG. 1 is a perspective view of a chair frame embodying the present invention;

See application file for complete search history.

FIG. 2 is a front view of the chair frame;

(56) **References Cited**

FIG. 3 is a first side view of the chair frame;

U.S. PATENT DOCUMENTS

FIG. 4 is a second side view of the chair frame;

5,725,276 A 3/1998 Ginat
5,772,282 A 6/1998 Stumpf et al.
5,871,258 A 2/1999 Battey et al.
5,975,634 A 11/1999 Knoblock et al.

FIG. 5 is a rear view of the chair frame;

FIG. 6 is a top view of the chair frame; and,

FIG. 7 is a bottom view of the chair frame.

The broken lines shown in the drawing are for illustrative purposes only and form no part of the claimed design.
